UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

51,123.

Specification for Design.

Patented Aug. 7, 1917.

Application filed June 19, 1917. Serial No. 175,701. Term of patent 3½ years.

To all whom it may concern:

Be it known that I, JOHN S. MONAGHAN, a citizen of the United States, and a resident of Rochester, Monroe county, State of New York, have invented a new, original, and ornamental Design for Buttons, of which the following is a specification.

My design is represented in the accompanying drawing, in which:

Figure 1 is a plan view showing my new design.

Fig. 2 is a section on line 2—2 of Fig. 1.

Fig. 3 is a side elevation looking in the direction of the arrow 3 of Fig. 1.

Fig. 4 is a side elevation looking in the direction of the arrow 4 in Fig. 1.

The button has an upper surface consisting of three inclined planes meeting with

each other at the center and at the respective inner edges thereof, the outer edge of each inclined plane being in the form of a sector, a raised rib forming the outer boundary of each inclined sector, said rib being substantially continuous, the upper surface of which is rounded.

I claim:

The ornamental design for a button substantially as shown and described.

In witness whereof I have hereunto set my hand at the borough of Manhattan, city and State of New York, this 18th day of June, 1917.

JOHN S. MONAGHAN.

In presence of—

ISABEL R. RICHARDS,
ZITA M. GRAHAM.
